UNITED STATES PATENT OFFICE

159,784

SHIP

William Costa, San Diego, Calif.

Application March 31, 1947, Serial No. 138,070

Term of patent 14 years

(Cl. D71—1)

To all whom it may concern:

Be it known that I, William Costa, a citizen of the United States and a resident of San Diego, in the county of San Diego and State of California, have invented a new, original, and ornamental Design for a Ship, of which the following is a specification, reference being had to the accompanying drawings, forming part thereof, wherein

Figure 1 is a side elevational view of a ship showing my new design.

Figure 2 is a stern view of the ship.

Figure 3 is a prow view of the ship.

Figure 4 is a side view showing the ship in a keeled-over position.

Figure 5 is an oblique bottom view of the ship. The characteristic features of my design re-

side in the portions shown by means of full lines in the drawing.

I claim:

The ornamental design for a ship, substantially as shown.

WILLIAM COSTA.
